DESIGN FOR A CAMERA SUPPORT

Neil J. Creedon, Glens Falls, N. Y.

Application August 31, 1944, Serial No. 115,151

Term of patent 7 years

(Cl. D61—1)

To all whom it may concern:

Be it known that I, Neil J. Creedon, a citizen of the United States, residing at Glens Falls, in the county of Warren and State of New York, have invented a new, original, and ornamental Design for a Camera Support, of which the following is a specification, reference being had to the accompanying drawing, forming part thereof.

I claim:

The ornamental design for a camera support, as shown.

NEIL J. CREEDON.
